UNITED STATES PATENT OFFICE.

JOHN MAXWELL, OF ONEIDA, NEW YORK.

COFFIN-FASTENER.

SPECIFICATION forming part of Letters Patent No. 369,198, dated August 30, 1887.

Application filed April 7, 1887. Serial No. 233,968. (No model.)

To all whom it may concern:

Be it known that I, JOHN MAXWELL, of Oneida, in the county of Madison, in the State of New York, have invented new and useful 5 Improvements in Lid-Fasteners for Burial-Caskets, of which the following, taken in connection with the accompanying drawings, is a full, clear, and exact description.

This invention has reference to lid-fasteners 10 designed more particularly for metallic burial-caskets, and relates to the class of lid-fasteners in which the lid-retaining clamps are connected to posts pivotally secured to the top of the casket and adapted to carry the clamps 15 in and out of their operative positions.

The object of my present invention is to simplify and reduce the cost of the attachment 20 of the clamp-carrying posts to the top of the casket; and to that end my invention consists, essentially, in the combination, with the casket and its lid, of sockets arranged along the top 25 of the casket, posts pivoted in said sockets, and clamps on the posts adapted to engage and retain the lid on the casket, all as hereinafter more fully described, and set forth in the claim.

In the accompanying drawings, Figure 1 is a vertical transverse section of the upper portion 30 of one side of the burial-casket with the lid secured thereto by my improved lid-fastener. Fig. 2 is transverse section of the metallic bar, which is attached to the top portion of the casket and has secured to it the post, which is provided with the lid-retaining 35 clamp. Fig. 3 is an isometric view of a section of the aforesaid bar, and Fig. 4 is a detached side view of the post to which the lid-retaining clamp is connected.

Similar letters of reference indicate corresponding parts.

A represents the side wall of the metallic burial-casket, having secured to its top a metallic bar, B, which projects over the exterior of the aforesaid wall in the usual manner.

L denotes the lid, which has secured to its base a stiffening-bar, a, by which it rests on the packing-strip b, placed upon the bar B, and is thus provided with an air-tight seat upon the casket. The outer projecting portion of the 45 bar B, I provide with a series of sockets, c c, which I prefer to form by drilling vertically through the bar cylindrical eyes, as shown in Fig. 2 of the drawings. In these sockets I

pivot the metallic posts P, which are formed at their feet with journals d, by which they 55 are stepped into the aforesaid sockets c c, and thus pivoted on the bar B, the post being provided with a shoulder, e, by which it rests on top of the bar B. The journal d is of sufficient length to pass completely through the 60 bar B, and terminates with clinching-prongs i i, which I spread or upset against the under side of the bar B, and thus retain the post P secured to said bar.

The aforesaid connection of the post P with 65 the bar B allows said post to be turned on its axis, so as to carry the lid-retaining clamp D in and out of its operative position. Said clamp may be of any suitable form, though preferably of the form of a cam or eccentric pivoted 70 on a horizontal arm projecting from the post, said cam and eccentric being adapted to bear on top of the stiffening-bar a, secured to the base of the lid L, as hereinbefore stated.

It will be observed that the described attachment of the post P to the bar B is effected 75 in a very simple and inexpensive manner, and the attachment is permanent and secure.

I do not wish to limit my invention to the retention of the pivoted post on the top bar of 80 the casket by clinching or upsetting the end of the journal of the post against the under side of the aforesaid bar, as it is obvious that the same object can be attained by inserting a 85 lynchpin in an eye extending transversely through the protruding end of the journal, and by other well-known means.

What I claim as new, and desire to secure by Letters Patent, is—

The combination, with a casket and its lid, 90 of bars secured along the top of the casket, smooth-bored sockets in said bars, posts formed with smooth journals stepped in said sockets and upset against the under side of said bars, and clamps on the posts adapted to engage 95 and retain the lid on the casket, as set forth and shown.

In testimony whereof I have hereunto signed my name and affixed my seal, in the presence of two attesting witnesses, at Oneida, in the 100 county of Madison, in the State of New York, this 2d day of April, 1887.

JOHN MAXWELL. [L.S.]
